LOCOMOTIVE

Frank Naylor Emory, Pittsburgh, Pa.

Application August 1, 1947, Serial No. 765,347

4 Claims. (Cl. 105—100)

1

The present invention relates in general to rail locomotives and in particular to the electric, Diesel, or turbine powered type. However, the principles of the invention may be applicable to other uses and may be employed on vehicles in general regardless of their nature.

Because of the ever present high cost of operations and maintenance of railroads, there has always been that constant drive to reduce these costs to a minimum. One way to reduce these costs is by increasing the efficiency of the locomotives and at the same time design a locomotive that will reduce the damaging effect upon the rails and road-bed of the railroads now being caused by the present locomotives.

Heretofore in order to obtain more draw-bar power from a locomotive of a given horse-power it has been necessary to increase its weight, its drivers, or both. This has in turn increased certain detrimental factors such as impact and flange friction, and it is with these factors in mind that the present improved features have been developed.

The broad object of the invention is to provide a locomotive which is more efficient in its operation and at the same time will have less damaging effect to the rails and to the railroad bed over which it is operated.

Another object is to provide a locomotive with centerless driving wheels, or rims, and means for efficiently operating the same.

Still another object being to provide a locomotive in which all the driving wheels may be provided with a smooth, flangeless tracking surface and means for maintaining the driving wheels upon the rails.

A further object being to provide an individual driving means for each of the driving rims and an internal and external braking mechanism therefor.

A still further object being to provide upon the frame individual suspension means for each of the driving rims.

A still further object is to provide a novel means for attaching front and rear pilot, or guide trucks, to the locomotive whereby the locomotive will be more centrally located in respect to the center of the rails when operated over curved tracks.

While several objects of the invention have been specifically pointed out, other objects and advantages will be more readily apparent as the nature of the invention is better understood and the same consists in the novel construction, combination and arrangement of parts shown in the

5 accompanying drawings forming a part of this specification and in which:

Figure 1 is a view in elevation of the locomotive showing in dotted lines the centerless driving rims.

Figure 2 is a plan view of the same.

Figure 3 is a view in side elevation or the forward half of the frame and forward truck, showing one of the centerless driving rims supported on the frame.

Figure 4 is a top plan view of the same.

Figure 5 is an enlarged fragmentary sectional view taken along the line 5—5 in Figure 3.

Figure 6 is a view in side elevation of the rearward portion of the frame and the rear truck showing another of the centerless driving rims as supported on the frame similar to that shown in Figure 3.

Figure 7 is a top plan view of the same.

Figure 8 is an enlarged fragmentary sectional view taken along the line 8—8 in Figure 7.

Figure 9 is an enlarged view in side elevation of the driving rim 8 showing diagrammatically the rim driving and supporting means.

Figure 10 is a sectional view taken along line 10—10 of Figure 9.

Figure 11 is an enlarged fragmentary sectional view taken along the line 11—11 of Figure 3 showing in particular the rim driving means, and the manner in which the driving means is supported in respect to the rim and upon the frame.

Figure 12 is an enlarged fragmentary sectional view of the driving rim showing more in detail one of the preferred forms of the rim supporting element.

Figure 13 is an enlarged fragmentary sectional view taken along the line 13—13 in Figure 6.

Figure 14 is an enlarged fragmentary sectional view taken along the line 14—14 in Figure 3.

Figure 15 is an enlarged view in elevation of one of the driving rims showing the manner in which the brakes are operated thereon.

Referring to the drawings in which like characters designate like parts throughout the several views, the locomotive in its general arrangement comprises a frame, a guide or pilot truck positioned at each end of the frame and at least one pair of relatively high centerless drive wheels, or rims, rotatably mounted on the frame between the guide trucks, the pairs of driving wheels, or rims, being oppositely disposed on each side of the frame with relation to each other so that each engages one of the two rails of the track.

More specifically the locomotive comprises a

rectangular frame 2 having its forward end 2' supported upon a forward pilot truck 4 and its opposite end 2'' supported upon a similar pilot truck 6. Both of these pilot trucks are constructed in substantially the same manner and a detailed description of one will be substantially the same for the other.

Positioned between the pilot trucks 4 and 6 and rotatably mounted upon the frame 2 is a plurality of centerless driving wheels, or rims, 8, 9, 10 and 11. But while the present embodiment shows four driving rims, the locomotive will operate on two drivers in substantially the same manner as it does on four.

In order to reduce flange friction, the driving rims are preferably flat, the outside circumferential surface of the wheel being relatively wide and substantially in a plane parallel with the axis of the rim.

The rims are also constructed to the maximum height of the locomotive, the theory being that by increasing the diameter of the driving wheel it will reduce impact and indentation of the wheel upon the rail and at the same time increase the traction surface of the wheel in contact with the rails.

The driving rims are provided in pairs, each pair being oppositely disposed, one on each side of the frame with a maximum of two pairs as shown in dotted lines (Figure 1). Each set of driving rims is preferably individually driven by a plurality of motors, the forward rims 8 and 9 being driven by the motor 14, 14' and 14'', while the rearward rims 10 and 11 are driven by the motors 17, 17' and 17'', and at points equi-distant about the circumference of the rims. However, any convenient number of motors may be employed which will give uniform and adequate rotating motion to the rim.

Referring in particular to Figure 11, one of the rim driving mechanisms is shown in detail. The motor 14 is shown as being supported substantially centrally of the frame 2 upon the supporting bracket member 15. The member 15 is in turn supported upon the shaft 18 adjacent the slideable bearings 16 and 16' by the arm portions 15' and 15'' of the bracket. Extending outwardly from each side of the motor 14 are shafts 19 and 20. The outer ends of these shafts being journaled within the bearings 21 and 21' which are also carried on the motor supporting bracket 15.

The bracket 15 is further supported and in particular against rotation on the frame 2 by the guide members 23 and 24, which are attached to the bracket arms 15' and 15'' and slidably connected with the frame 2. These guides act to keep the bracket arms 15' and 15'' in line with the channels in the frame accommodating the slideable bearings 16 and 16'.

The rims as constructed are preferably provided with a smooth flat outer surface for contacting the rail head, the inner peripheral surface thereof having central rib members or strengthening members 33 and 33' extending inwardly from the surface for reinforcing the same. On one side of the central rib are smooth surfaces 34 and 34' for receiving gear spacing rolls 28 and 28', and on the opposite side of the rib there are provided ring gears 32 and 32'.

While the outer surfaces of the rims are shown in the present embodiment of the invention to be smooth, or flangeless, they may also be provided with the customary flanges if desired, or if the locomotive is to be operated without the pilot trucks.

Fixably secured adjacent each outer end of the shafts 19 and 20 are gears 25 and 26, which are in turn adapted to engage the large gears 29 and 30. These gears are fixably secured to the shaft 18 which rotate in the bearings 16 and 16'. The gear spacing rolls 28 and 28' may also be secured to the shaft 18 and are adapted to bear against the inner peripheral surfaces 34 and 34' of the rim for regulating the depth of the engaging gear teeth of the gears 22 and 22' with those of the ring gears 32 and 32'. These gears 22 and 22' are also fixably secured to the shaft 18 and are adapted to rotate the rims through the ring gear teeth 32 and 32'.

Referring to Figure 12, the rim strengthening members 33 and 33' may be tapered slightly in order to give ample clearance between them and the driving gear 22 and the gear spacing roll 28.

As all the rim drivers are of the same construction, and as both sets of driving rims are operated in the same manner, only one detail description is given for the rim structure and rim driving mechanism.

Referring again to the pilot, or guide trucks, the front truck is provided with a frame 4 having two or more sets of substantially low wheels 40, 41, 42, 40', 41' and 42' carrying the standard flange. These wheels are supported on axles 44, 45 and 46 which are in turn mounted in the journal boxes 48, 49, and 50 and journals 48', 49' and 50' (not shown) located on the opposite sides of the frame 4 for supporting the opposite ends of the axles.

For each pair of driving rims there is provided a major weight carrying element such as rollers 71 and 71'' as shown in Figures 3 and 6. These elements are adapted to roll upon the smooth inner surface of the rims and are carried by a single axle which is journaled in appropriate bearings on each side of the frame similar to the bearings 79 and 79'' as shown in Figures 3 and 6. There is also provided for each of the rims, in addition to the major supporting rollers 71 and 71'', idling rollers 72 and 73 as shown best in Figure 9 which are also adapted to engage the smooth inner circumference of the rim and above the center line of the rim at approximately 45° from the center of the rim. These idlers are held outwardly against the rim by springs similar to those shown at 74 and 75 in Figure 3 and are for aiding in the normal support of the upper portion of the rim in relation to the frame.

The pilot trucks 4 and 6 are located at each end of the locomotive frame 2, and both are mounted to the frame in substantially the same manner. Referring in detail to the mounting arrangement, reference is made primarily to the pilot truck shown in Figure 3. The truck is mounted to the forward end 2' of the frame upon a pivot pin 60 which is located substantially over the center of the axle 44. The weight of the frame being carried upon a bearing 61 which is located substantially centrally of the truck. Located centrally of the frame is a roller 62 which is mounted to a cross member 62', the roller being adapted to bear upon the bearing plate 61.

The rear truck 6 is of substantially the same construction as the forward truck and is pivoted to the frame 2 by the pin 63, the weight of the rear end of the frame being carried upon the roller 64 which is in rolling contact with a bearing plate 65, the roller being located at a point substantially in the center of the truck 6.

The pilot truck wheels of the two trucks are arranged in a similar manner. Referring to Fig-

ure 13, the sectional plan view shows the arrangement of the wheels of the rear truck 6, each pair of wheels being oppositely disposed on each side of the truck and supported upon a single axle. All of the truck wheels are provided with the conventional type flanges. The wheels 51, 51', 52, 52', 53 and 53' are fixably attached adjacent each end of the axles 43, 43' and 43'', respectively, the outer ends of the axles being journaled within the journal boxes 54, 54', 55, 55', 56 and 56'. The pivot pin 63, connecting the frame 2 with the truck, is located substantially over the center of the axle 43'' similar to the location of the forward pivot pin 60, it being located over the axle 44 of the forward truck. The pair of wheels located adjacent the pivot pin 63 are slightly farther apart than any of the remaining pairs in order to place the flanges of this pair of wheels nearer the rails 3 and 3'. This is to reduce the side sway of the end of the truck to which the main frame 2 is pivoted. The greatest clearance between flanges and the rails is in the outer wheels as shown at 51 and 51', while the center pair of wheels 52 and 52' show approximately one-half the clearance between the flanges and rails as the wheels 51 and 51'. Also there is provided in the journal boxes 55 and 55' an allowance for a limited amount of end play for the shaft 43'. The purpose of this particular arrangement is to provide a pilot truck which will be able to negotiate standard track curves and at the same time provide a truck having a minimum amount of side sway at the point it is coupled or pivoted to the main frame. The purpose of this design being to reduce the side sway of the locomotive. Even though the outer portion of the pilot trucks may have a normal swaying movement, the portion of the truck guiding and positioning the main frame and drivers over the rails will reduce to a minimum the side motion.

Located at the front end of the locomotive and in front of the forward driving rims is a control and operating room 70, and at the opposite end over the rear truck 6 is a compartment 70' for machinery or fuel storage space.

The gears 22 and 22', as shown best in Figure 11, are held in contact with the ring gears 32 and 32' by the springs 76 and 77 which also hold the spring spacing rollers 28 and 28' in contact with the rim portion 34 and 34'.

The enlarged sectional view in Figure 14 shows the manner in which the slidible members 78 are carried on the frame to allow movement relative to the frame.

The braking mechanism on the pilot trucks is of the conventional type and is not shown. The braking mechanism for the centerless driving rims comprises outer shoes 90 and 91 and inner shoes 92 and 93. The outer shoes are adapted to contact the outer circumference of the rim while the inner shoes are adapted to contact the smooth inner portion 34 and 34' of the rim. The outer shoes 90 and 91 are mounted on the outer end of the operating arms 94 and 94', the inner end of the arms being attached to a rotatable drum 95. The inner shoes 92 and 93 are attached to the outer end of the operating arms 96 and 97, which in like manner have their opposite ends attached to the drum 95. The drum 95 is rotatably mounted on the shaft 98, the shoes being held in braking position adjacent the rim by brackets 99 and 100, 101 and 102 which are secured to the frame. In order to mechanically operate the brakes there is provided a cylinder

103 and a piston rod 104, the piston being operated by air or other well-known fluids. The circulation of the fluid may be controlled by a three-way valve 105 of any well-known make. When the valve is in one position, the fluid, under pressure, enters the cylinder 103 through the lead pipes 106 and 107 and when the valve is in opposite position the fluid is exhausted through pipes 107 and 108. In operating the piston in this manner an arm 109 may be likewise operated, the arm 109 being connected to the piston at 111 and pivoted at a point 112. The arm 109 is bent at right angles to form the portion 112', and connected to the outer portion 112' is a link 113. The link is connected to the arm 115 which is in turn connected to the drum 95 at 98. When the piston is moved inwardly the portion 112' of the arm is moved upwardly, the link 113 being pivotably connected with the arm 115, which is fixably connected to the drum 95 and will rotate the drum in the direction of the arrow (Figure 16). Through the connecting arms 94, 94', 96 and 97 the outer brake shoes will be moved inwardly upon the rim and the inner shoes will be moved outwardly on the smooth portions of the rims, the action of the inner and outer braking shoes being substantially in the same area along the inner and outer surfaces of the rims.

In operation the general arrangement of the locomotive is shown best in Figure 1, the frame and the centerless driving rim being shown in dotted lines. The pilot trucks 4 and 6 are positioned under each end of the frame while the driving rims are rotatably mounted to the frame between the trucks. The principal weight carrying element being the pair of rollers 71 and 71' which bears against the smoother inner surfaces of the rims at a point substantially above the contact point between the rims and the rails. In this particular design the centerless rims are flangeless, the driving rims being positioned over the rails by the pilot trucks which are pivoted as near the driving rims as possible. As previously described, all the pilot truck wheels are provided with flanges. By having the pilot trucks 4 and 6 pivoted as near the driving rims as possible, the center of the frame will remain nearer the center of the rails when the locomotive is on a curved track. By having the first pair of truck wheels nearest the main portion of the frame farther apart, the flanges will be nearer the rails which will reduce swaying of the truck and of the locomotive as the pivot pins are located directly over these wheels. The other wheels of the truck are slightly closer allowing more tolerance between the wheel flanges and the rails which is necessary when operating over curved tracks. The principle of operation may also be carried out with only two high driving rims oppositely disposed on opposite sides of the frame in which there would be two drivers in place of the four shown. However, for maximum efficiency the locomotive is particularly designed with four driving rims.

Over the frame and the driving rims is a housing 115. The driving rims extend upwardly and occupy substantially the full height of the housing. As the driving rims are without a center axle, the space between the rims is reserved for operating machinery in addition to the space over the forward and rear pilot trucks, the forward end of the housing being arranged primarily as an operating and control room.

The invention is not to be limited to the exact arrangement of parts as shown in the accom-

panying drawings or as described in this specification as various changes in the details of construction may be resorted to without departing from the spirit of the invention, and only in so far as the invention has been particularly pointed out in the accompanying claims is the same to be limited.

I claim:

1. A rail traversing machine comprising a rigid frame having a plurality of independently supported flangeless, centerless rail engaging rims rotatably mounted on each side of the said frame, the inner surface of the said rims being provided with a smooth and toothed area, rotatable supports for said frame adapted to engage the smooth area of the inner circumference of the rim adjacent the rail engaging regions thereof, an internal driving gear for each of the said rims adapted to engage the toothed area of the rim and means adjacent each end of the said frame for positioning the said flangeless rims over the rails.

2. A rail traversing machine comprising a rigid frame having a plurality of independently supported flangeless, centerless rail engaging rims rotatably mounted on each side of the said frame, the rim surface of the said rims being provided with a smooth and toothed area being of substantially the same diameter, rotatable supports for said frame adapted to engage the smooth area of the inner circumference of the rim adjacent the rail engaging regions thereof, an internal driving gear for each of the said rims adapted to engage the toothed area of the rim and means pivotably mounted adjacent each end of the said frame for positioning the said flangeless rims over the rails.

3. In a rail locomotive comprising a rigid frame, a separate truck unit pivotably mounted to each end of the said rigid frame having two or more pairs of relatively low flanged wheels engaging said rails for positioning the frame relative to the said rails, driving means carried

by said frame between the said trucks comprising at least two relatively light flangeless track engaging centerless rims rotatably mounted on opposite sides of the said frame and each oppositely disposed with relation to each other and a housing adapted to cover the said pivotably mounted trucks and rigid frame substantially as described.

4. In a rail locomotive comprising a rigid frame, a plurality of rail engaging flangeless, centerless driving rims rotatably mounted on each side of the said frame, the inner surface of the said rims being provided with a smooth and toothed area being of substantially the same diameter, rotatable supports for said frame adapted to engage the smooth area of the inner circumference of the rim adjacent the rail engaging regions thereof, an internal driving gear for each of the said rims adapted to engage the toothed area of the rims, a rotating guiding support for said gear mounted in a plane substantially parallel therewith adapted to engage the smooth inner area of the rim for guiding the meshing of the driving gear and the rim gear and means pivotably mounted adjacent each end of the said frame for positioning the said flangeless rims over the rails.

FRANK NAYLOR EMORY.
